US00D973855S

(12) **United States Design Patent** (10) **Patent No.:** **US D973,855 S**
(45) **Date of Patent:** **** Dec. 27, 2022**

(54) **INTERCOOLER CORE**

(71) Applicant: **Whipple Industries, Inc.**, Fresno, CA (US)

(72) Inventors: **Dustin E. Whipple**, Fresno, CA (US); **Garrett Wayne Bright**, Clovis, CA (US)

(73) Assignee: **WHIPPLE INDUSTRIES, INC.**, Fresno, CA (US)

(**) Term: **15 Years**

(21) Appl. No.: **29/754,629**

(22) Filed: **Oct. 13, 2020**

(51) **LOC (13) Cl.** **23-04**

(52) **U.S. Cl.**

USPC **D23/351**

CLAIM

The ornamental appearance of an intercooler core, as shown and described.

DESCRIPTION

FIG. 1 is a top perspective view of an intercooler core.

FIG. 2 is a bottom perspective view of the intercooler core.

FIG. 3 is a front elevational view of the intercooler core.

FIG. 4 is a rear elevational view of the intercooler core.

FIG. 5 is a top plan view of the intercooler core.

FIG. 6 is a bottom plan view of the intercooler core.

FIG. 7 is a left side elevational view of the intercooler core; and,

FIG. 8 is a right side elevational view of the intercooler core. The broken lines shown in the drawings depict portions of the intercooler core that form no part of the claimed design.

1 Claim, 6 Drawing Sheets
